UNITED STATES PATENT OFFICE

GEORGE A. HILLERY, OF NEW ORLEANS, LOUISIANA

COOLING MECHANISM

Application filed September 27, 1930. Serial No. 484,881.

The object of this invention is to provide a mechanism which will operate automatically and by which the air flowing into buildings, assembly rooms or other places may be reduced in temperature so as to eliminate uncomfortable and enervating high temperatures within rooms or buildings. The invention provides a mechanism whereby brine or other temperature-controlling liquid will be caused to flow over a prescribed path and air will be drawn into the apparatus to follow the flow of the brine and, by commingling therewith, lose its heat. The invention seeks to provide an apparatus for the stated purpose in which the air will be caused to circulate over a tortuous path and pass a plurality of baffles so as to be subjected constantly to the action of a cooling spray and be eventually discharged at a reduced temperature. The invention also seeks other objects which will incidentally appear in the course of the following description. An apparatus embodying the invention is illustrated in the accompanying drawings and will be hereinafter first fully described and then more particularly defined in the appended claims.

In the drawings:

Figure 1 is a side elevation of an apparatus embodying the invention,

Fig. 2 is a longitudinal vertical section,

Fig. 3 is a horizontal section on the line 3-3 of Fig. 2,

Fig. 4 is a transverse section on the line 4-4 of Fig. 3,

Fig. 5 is a section on the line 5-5 of Fig. 2, and

Fig. 6 is a section on the line 6-6 of Fig. 3.

In carrying out the invention, a casing 1 is disposed upon a brine tank 2 within which tank is a circulating cooling coil 3. The coil 3 extends the full length of the brine tank, as shown in Fig. 2, and it may be a direct expansion ammonia coil or may be connected with a circulating pump so that cooling water or other agent may be positively driven through the same or it may merely have its ends extended through the opposite end walls of the brine tank and exposed to the atmosphere so

that air will circulate through the coils. The brine tank is equipped with a cover 4 which is somewhat larger than the bottom of the casing 1 so that any moisture which may condense upon the walls of the casing will be caught and not permitted to collect upon the floor of the cooling room. Openings 5 are formed through the cover to permit the condensate to drain into the brine tank and a flange or rib 6 is formed upon the cover in spaced relation to the casing so as to arrest any condensate which may tend to flow from the side edges of the cover. Connected with one end of the brine tank is an outlet pipe 7 which extends to the inlet side of a pump 8 which may be of any preferred form and is illustrated conventionally, a return pipe 9 leading from the outlet side of the pump into the casing 1 so that the cooled brine will be forced into the circulating system within the casing 1 after it has passed through the entire length of the brine tank. A complete cycle will then be established so as to effect continuous circulation of the brine and resultant cooling effect upon the air.

The casing 1 has a door 10 which is provided at one end to permit inspection when necessary. This door 10 has its edges slidably engaged in cleats or re-entrant flanges 11 formed on the casing at the sides of the door opening and is equipped at its upper end with a finger piece or handle 12, and at its lower end has an inset lip or flange 13 which is adapted to engage behind the wall of the casing at the lower end of the door opening, a similar lip or flange 14 being formed on the casing wall at the upper end or side of the door opening to engage behind the door so that the door will be effectually held in proper position and escape of the brine or other cooling agent around the door will be prevented. The pipe 9 passes into the casing below the door 10, as clearly shown in Fig. 2, and within the casing is connected directly to a manifold 15 from which spray pipes 16 rise to a desired height within the casing or cooling chamber. As best shown in Fig. 5, there are preferably three pipes 16 and upon each pipe are five spray nozzles 17, the nozzles upon the respective pipes being

relatively staggered so that the sprays issuing therefrom will be dispersed over a substantial area. Extending across the casing adjacent the upper ends of the spray pipes 16 is a deflector 18 which is curved rearwardly at its upper end and terminated short of the roof or ceiling of the casing while its lower end is also curved rearwardly or downwardly and to a lesser degree, the lower end of this deflector having a lip or flange 19 extending along the same to catch the moisture and brine which collect on the deflector and prevent dropping thereof directly across the stream of air flowing through the cooling chamber, draining to the sides of the chamber being set up so as not to interfere with the circulation. For convenience the end of the casing having the door 10 will be referred to as the front end. At the lower front corner of the casing is a curved guide plate or fender 20 which serves to direct the air in a curve toward the rear end of the casing and prevent the air flowing into the sharp corner where it would be apt to form eddies and frustrate the object of the invention. Rising from the supply pipe 9 between the end wall of the casing and the spray pipes 16 is a branch pipe 21 which extends close to the ceiling 22 of the cooling chamber and is then turned rearwardly to travel longitudinally of the casing immediately below the ceiling, as shown at 23. The rear end of the pipe 23 is equipped with a transverse spray head 24 disposed close to the rear end wall of the casing and also close to the ceiling thereof, as best shown in Fig. 2. A series of intake funnels 25 is provided on the casing and these funnels may, of course, be provided in any desired number according to the size of the apparatus and the demands to which it is subjected, four funnels being shown in the present drawings. These funnels provide wide intakes for the air which is to be treated and are provided with flaring mouths, as indicated at 26, the delivery ends of the funnels being fitted within flanges or collars 27 on the roof of the casing and being of less diameter than the mouths so that the flow of air will be accelerated as the air approaches and enters the casing. A branch pipe 28 rises from the branch 23 below the delivery end of each funnel and said pipes enter the respective funnels, as shown in Fig. 4, each being coupled within the respective funnel to a spray head 29 extending toward the rear wall of the funnel and equipped with spray nozzles 30 which are directed downwardly so that the liquid issuing therefrom will pass downwardly toward and into the casing and will act directly upon the inflowing air to increase the speed of the same. Each pipe 28 is coupled to a branch 31 which extends towards the mouth of the respective funnel and has its end turned upwardly, as shown at 32, said upturned end having a fitting 33 and

a manifold 34 which are equipped with inwardly directed spray nozzles 35, as shown, the fitting having a single nozzle and the manifold 34 and spray head 29 each having three nozzles. It will thus be seen that as the air enters the funnels it is at once subjected to the action of sprays issuing from the nozzles 35 so that it will be accelerated in its flow and will be broken up and modified in temperature by contact with the spray, the nozzles being so located that their force is applied over the entire cross-sectional area of the body of air. It will also be noted that spray nozzles are located at the points where the direction of flow of the air changes so that the force of the spray is exerted to aid in deflecting the air as well as to reduce the temperature of the same.

An upper baffle or partition 36 is provided in the upper portion of the casing or cooling chamber and this partition extends from the upper rear corner of the casing under the spray nozzle head 24 downwardly toward the deflector 18, terminating in spaced relation to said deflector. A spray head or manifold 37 is connected with the branch pipe 23 and extends downwardly and rearwardly therefrom approximately at an angle of forty-five degrees, the spray nozzles 38 thereon being directed downwardly and forwardly and so disposed that the liquid issuing therefrom will pass to opposite sides of the deflector 18. The air which passes in through the funnels will enter the top of the casing or cooling chamber and the funnel at the front end of the casing will discharge its air at the front of the deflector 18 while the other funnels will discharge air downwardly toward and upon the partition or baffle 36 at the rear of the deflector 18. The brine which enters with the air will, of course, pass downwardly at the front of the deflector 18 or downwardly onto the partition 36 and the liquid which is discharged onto the partition will travel downwardly toward the lower front end of the same. The lower front end of the partition 36 is disposed below and in spaced relation to the upturned end member 39 of a false ceiling 40, which extends to the rear end of the casing and is so disposed that the moisture collecting thereon will be directed to a drain 41 whereby it will pass down to the floor of the cooling chamber and eventually escape into the brine tank through a drain outlet 42. The provision of this false ceiling 40 with the upturned end member 39 permits the desired circulation of the air to take place and serves to collect the moisture and brine and return the same to the brine tank so that excessive humidity in the air eventually discharged from the casing will be avoided. The drain 41 which has just been mentioned is defined by a vertical plate 43 disposed at the corner of the casing and curved in its horizontal dimension so as to

present a stream line to the air and avoid eddying of the same, the lower portion of the plate 43 being cut away to define an opening 44 whereby the brine at the rear of the plate may find its way to the drain 42. The drain 42 is defined by a ring or collar depending from the cover 4 of the brine tank to a point below the normal level of the brine in the tank so that aeration of the brine will be avoided and corrosion of the cooling coil will be minimized. To prevent eddying of the brine which may collect upon the floor of the cooling chamber as it flows to the drain 42, deflecting strips 45 are provided on the floor of the chamber at the opposite sides of the drain, as best shown in Fig. 3.

From what has been said, it will be understood that the air flowing in through the several funnels is at once acted upon by sprays of brine or other liquid, or possibly gas, and the flow of this fluid agent will at once accelerate the flow of the air so that it will pass over the prescribed course, flowing downwardly over the partition 36 and downwardly past the deflector 18 and then rearwardly below the false ceiling 40 to eventually pass out through a discharge opening 46' in the side of the casing near the rear end thereof. The air initially is flowing at a much slower rate than the spray from the several nozzles inasmuch as the brine or other agent is subject to the pressure of the pump 8. The air, therefore, tends to resist the flow of the brine and in doing so commingles with the brine so that the brine absorbs the heat from the air and is, in turn, broken up or rarefied so that the air will become laden with the brine. The apparatus in actual practice may be provided with thermostatic controls to regulate the speed of the pump and the periods of its operation and this, in turn, will regulate the humidity imparted to the air as it flows through the cooling chamber. These thermostatic controlling devices are well known and are in common use for automatically controlling temperature and form no part of the present invention and are, therefore, not illustrated. As the air flows rearwardly below the false ceiling 40, it flows over the floor of the cooling chamber which is, of course, covered with brine dropping thereto from the air and from the several nozzles so that the heat remaining in the air after it passes the nozzles 17 will be further reduced by the action of the brine upon the floor of the cooling chamber. Before the air can escape, it must flow past baffles 46 which extend vertically and are disposed at an angle to the path of the air, as shown best in Fig. 3. The baffles 46 lead directly to similar baffles 47 which are provided in a greater number than the baffles 46 and are arranged substantially at a right angle thereto. The rear ends of all these baffles are provided with hooks or re-entrant flanges 48 which check the flow of brine ad-

hering to and condensing on the several baffles so that said brine cannot pass around the edges of the baffles to obstruct the flow of the air but will drain to the floor of the cooling chamber. At the rear of the baffles 47 are baffles 49 which are similar to the first-described baffles but are provided in greater numbers than the baffles 47 and substantially at a right angle thereto so that the course of the air will be again diverted, and immediately at the rear of the baffles 49 are vertical baffles 50 which are disposed parallel with the sides of the cooling chamber. At the rear of the baffles 50 are horizontal baffles 51 which are substantially V-shaped and are provided with drains 52 whereby the water of condensation and adhering brine will be turned to the sides of the casing and discharged onto the floor of the same so as to avoid obstructing the flow of the air. These several baffles may be constructed as units, the several baffle plates having their ends secured to frame plates, indicated at 53, and then the completed unit pushed into the casing through an opening 54 in the side of the same, said opening being covered by a door plate 55 which is fastened to the side of the casing, as will be understood upon reference to Figs. 1 and 3, and will serve to prevent premature discharge of the cooled air and escape of the brine or other temperature-regulating agent.

Immediately at the rear of the horizontal baffles 51, arcuate deflecting plates 56 and 57 are provided which curve from the baffles 51 around to points adjacent the drain 42, as shown clearly in Fig. 3, and at the terminals of these deflecting plates or baffles 56 and 57 are horizontal baffles 58 which extend across the outlet opening 46 for the full height of said opening. These baffles 58 are inverted V-shaped in cross section, as seen in Fig. 4, and are provided at their centers and at their inner edges with re-entrant flanges 59 to collect the water of condensation and at their front edges are provided with similar flanges 60 on their under sides for the same purpose, it being understood that the cooled air with its moisture content will impinge against the under sides of the outer portions of these baffles. A deflecting plate 61 is provided between the baffles 51 and the front ends of the baffles 58, as shown in Fig. 3, so that the air will not be permitted to pass directly to the baffles 58 nor collect in the corner defined by said baffles and the adjacent side wall of the casing to form eddies. Horizontal divider plates 62 extend from the rear of the baffles 51 and intersect the forward portions of the deflector plates 56 and 57. The cooled air, as has been stated, will discharge through the opening 46' past the baffles 58 and will then circulate within the room or building, the temperature of which is to be reduced. The apparatus is very efficient in action and needs

little attention. A very perceptible lowering of the temperature will be accomplished in a short time and the operation of the apparatus will not be resumed until the temperature again reaches the maximum, whereupon the pump will automatically start and cause the circulation of the brine to again lower the temperature. While I have described the apparatus as intended for reducing temperature in a building or room, it is to be understood that it may be used for heating. To accomplish this result, superheated steam or other highly heated agent may be circulated through the coils 3 to raise the temperature of the fluid in the tank and which is to be circulated through the several pipes and spray nozzles. If desired, the air thus circulated may be made to carry some moisture content so as to impart a desired degree of humidity to the air in the building or room.

20 A trap door 63 is provided at one end of the brine tank so as to facilitate the replenishing of the supply of brine or inspection of the cooling coils when such replenishing or inspection is desirable.

Having thus described the invention, I claim:

1. An apparatus for the purpose set forth comprising a casing, a false ceiling within the casing having a free end spaced from the front end of the casing, a deflecting plate above said ceiling and converging toward the free end of the same from an upper rear corner of the casing, means for admitting air 30 to the casing above said deflecting plate, and means for discharging a cooling agent into the air under pressure whereby to accelerate the circulation of the same, the air and cooling agent flowing over said deflecting plate 35 and back under the false ceiling to a discharge opening in the casing.

2. An apparatus for the purpose set forth comprising a casing, a false ceiling within the casing extending from the rear end thereof and terminating short of the front end thereof, an upturned member at the end of the false ceiling, a funnel rising from the casing and in communication therewith to admit air thereto, a deflecting plate extending from 45 an upper rear corner of the casing to said upturned member and terminating adjacent and below the edge of said member, a supply pipe entering the casing for delivering a cooling agent under pressure, spray nozzles connected with said pipe and disposed within the funnel and delivering a cooling agent under pressure in the direction of flow of the air, and other spray nozzles connected with said pipe and arranged to deliver a cooling agent 50 under the false ceiling.

3. Apparatus for the purpose set forth comprising a casing, a funnel on the casing arranged to deliver air through the top of the casing, a supply pipe entering the casing 65 at the front end of the same for deliver-

ing a cooling agent under pressure, spray nozzles connected with said pipe and arranged within the funnel to deliver a cooling agent in the direction of flow of the air, a manifold connected with the supply pipe 70 within the casing, spray pipes rising from said manifold adjacent the end of the casing, spray nozzles arranged upon the several spray pipes in staggered relation and disposed to discharge a cooling agent into the air in the 75 direction of flow of the air, a false ceiling in the casing extending from the rear end thereof to a point above said manifold, and a deflecting plate above said ceiling diverting air and cooling agent to the front end of the 80 ceiling.

4. In an apparatus for the purpose set forth, a casing, a supply pipe entering the casing to deliver a temperature-regulating medium under pressure, funnels on the casing 85 to deliver air thereinto, spray nozzles connected with the supply pipe and arranged within the funnels to deliver the temperature-regulating medium in the direction of flow of the air, a plurality of spray nozzles 90 connected with the supply pipe adjacent an end of the casing, a deflector arranged adjacent said nozzles and having its upper and lower ends curved rearwardly, a deflecting plate in the upper portion of the casing leading from an upper rear corner of the same 95 downwardly to said deflector and terminating short of the deflector, spray nozzles connected with the supply pipe adjacent the upper end of the deflector and arranged to deliver temperature-controlling medium at the front and the rear of the deflector, a false ceiling within the casing below the deflecting plate and provided at its inner end with a guide member extending upwardly and terminating 100 adjacent and above the end of the deflecting plate, means for discharging cold air from the casing, and means for discharging the condensed temperature-controlling medium 105 from the casing.

5. In an apparatus for the purpose set forth, a casing having an air outlet in one side at one end, a false ceiling within the casing, means for admitting air to the casing above said ceiling, means for discharging a temperature-controlling medium under pressure into the air, a drain at one end of the false ceiling leading therefrom to the bottom of the casing to permit escape of condensate, a drain 115 through the bottom of the casing, and a plurality of baffles disposed between the false ceiling and the floor of the casing and extending alternately in opposite directions and alternately vertically and horizontally, some of the baffles extending across the air outlet 120 of the casing.

6. In an apparatus for the purpose set forth, a casing, a false ceiling in the casing, means for admitting air to the casing, means for discharging a temperature-regulating me- 130

dium into the air at various points to control the circulation of the air, a plurality of baffles arranged between the false ceiling and the floor of the casing at and adjacent the rear 5 end of the same, some of said baffles extending vertically and some horizontally, the vertically extending baffles being disposed at right angles to each other, curved deflecting plates extending from the horizontal baffles rearwardly 10 toward the outlet opening of the casing, a drain through the floor of the casing adjacent the outlet of the same, horizontal baffles extending across the air outlet, and baffles disposed adjacent the drain to prevent 15 eddying at the same.

In testimony whereof I affix my signature.
GEORGE A. HILLERY. [L.S.]
